UNITED STATES PATENT OFFICE

2,410,628

FIREPLACE WOOD ELEVATOR

Louis P. Brunette, Farmington, Conn.

Application July 9, 1945, Serial No. 603,959

4 Claims. (Cl. 187—3)

1

This invention relates to elevator apparatus, and more particularly to a fireplace wood elevator which is adapted to raise cord wood from the cellar of a house to a compartment located alongside a fireplace above the cellar.

One object of the present invention is to provide an elevator apparatus of the above nature in which the elevator platform is operated by means of a pair of motor-driven sprocket chains connected to the rear of said platform, and having means for transmitting the lifting force from the rear to the front of said platform whereby said platform will be maintained in a level condition at all times and with the minimum of friction.

A further object is to provide an apparatus of the above nature in which the sprocket chain has a laterally projecting lug which is adapted to engage a pair of circuit-opening switches when the elevator reaches either the top or bottom of its motion, respectively.

A further object is to provide an apparatus of the above nature which will be relatively simple in construction, inexpensive to manufacture, easy to install and manipulate, compact, ornamental in appearance, and very efficient and durable in use.

With these and other objects in view, there has been illustrated on the accompanying drawings one form in which the invention may conveniently be embodied in practice.

In the drawings,

Fig. 1 represents a sectional view of the cellar and first floor of a dwelling house, showing the improved elevator apparatus arranged for lifting cord wood from the cellar to a compartment adjacent a fireplace on the first floor.

Fig. 2 is a horizontal sectional view on a larger scale of the elevator shaft showing the relative location of the elevator platform, the reversible driving motor, the operating sprockets and chains, and the lift-equalizing cables.

Fig. 3 is a front elevation of the same, shown partly in section.

Fig. 4 is a side elevation of the same, also shown partly in section.

Referring now to the drawings in which like reference numerals denote corresponding parts throughout the several views, the numeral 10 indicates a base plate which is adapted to rest upon the cellar floor 11, as clearly shown in Figs. 1, 3, and 4. The elevator and shaft are adapted to be enclosed on three sides by a U-shaped frame 12 mounted on the base plate 10 and extending to the ceiling of the cellar below the first floor 20.

2

The base plate 10 is provided with a side extension 13 which serves to support a reversible motor 34, the operation of which will be described later.

5 Located within the U-shaped frame 12 are four vertical pillars 14, 15, 16, and 17 arranged at the corners of a rectangle, and surmounted at their tops by a horizontal rectangular housing 18 having a rectangular aperture 19 through which wood 10 carried by an elevator platform 27 is adapted to pass upwardly. The elevator shaft is adapted to be located alongside the base 21 of a brick fireplace 22, herein shown as located on the first floor 20, said fireplace having a mantel shelf 23 15 above it.

A compartment 24 is located at the left of the fireplace for the storage of cord wood or any other articles. The storage compartment 24 is provided with a pair of outwardly opening hinged 20 doors 25 which are identical in appearance with a similar pair of hinged doors 26 located at the front of a similar cord wood compartment 24a positioned above the top of the elevator shaft.

The elevator platform 27 has a quantity of 25 cord wood 27a resting upon it, and is supported in an offset position spaced upwardly from an open frame 28 by means of a plurality of vertical rods 29.

In order to guide the front of the elevator with 30 the minimum of friction, provision is made of a plurality of concave rollers 30, 31 located on the front and rear of the front pillars 14, 15, respectively. The forward rollers 30 are mounted in horizontal brackets 32 which are rigidly connected at their rear ends to the bottom of the open frame 28. The rollers 31 are connected to brackets 33 which are rigidly mounted on the forward vertical supporting rods 29, as clearly shown in Fig. 4.

40 For the purpose of driving the elevator up and down in the shaft within the frame 12, provision is made of a reversible electric motor 34 having a driving shaft 35 upon which is mounted a pinion 36 meshing with a gear 37. The gear 37 is mounted upon a horizontal shaft 38 located within the frame 12 and journaled in a pair of upstanding bearing brackets 39, 39 resting on the base plate 10. Rigidly mounted on the shaft 38 are a pair of lower sprocket gears 40 having a 45 pair of sprocket chains 42 meshing therewith, said sprocket chains passing upwardly within the U-shaped frame 12 and around a similar pair of upper sprocket gears 41 mounted upon a top horizontal shaft 42a, journaled in bearing brackets 50 42b, as clearly shown in Fig. 3.

One end 43 of each chain 42 is fixed to the open frame 28 and said chain, after passing around the upper and lower sprocket gears 41 and 49 has its free end 44 secured to an adjustable angle bracket 45 which is suspended from said frame 28 by means of an adjusting bolt 46 having a head 47 on its lower end, and a pair of nuts 48 on its upper end located above said frame 28.

In order to cause the stopping of the platform 27 when it has reached its upper or lower positions within the elevator frame 12, provision is made of a pair of stop switches 49, 50, rigidly secured in adjusted positions adjacent the upper and lower ends of the vertical pillar 16, said switches being adapted to be engaged by a laterally-extending lug 51 adjustably secured on the free end of the righthand chain 42, in such a position that the switches 49, 50 will be actuated to open the motor circuits when the wood-carrying platform 27 has reached its upper and lower positions, respectively, as mentioned above.

If desired, provision may be made of a circuit breaker (not shown) which will be actuated when engaged by the pile of wood 27a stacked upon the platform 27 to shut off the elevator motor in case said pile of wood is excessively high.

Provision is also made of a manually-operated reversible motor switch 52, herein shown as conveniently located above the cord wood compartment of the elevator.

For the purpose of providing a lifting force at the front of the elevator platform 27 equal to that applied by the sprocket chains 42 to the rear of the platform, and thus maintain said platform level, provision is made on both sides of the U-shaped frame 12 of three pulleys 53, 54, 55, having a cable 56 running thereover—said cable having one end 57 adjustably connected to the angle bracket 45, and its other fixed end 58 is connected to the horizontal bracket 32 extending forwardly from the frame 28.

Operation

In operation, when it is desired to use the elevator, the cord wood 27a will be loaded on the platform 27 in the cellar, and the operator will turn the switch 52 in such a direction as to cause the motor to drive the elevator upwardly. 50

When the elevator reaches the raised position shown in Fig. 1, the lug 51 will engage the switch 49 and automatically open the motor circuit, stopping further movement of the platform.

5 When the operator wishes to return the platform to the basement, it will only be necessary for him to throw the switch 52 in the reverse direction, causing the motor 34 to drive the platform 27 downwardly, until the lug 51 engages the circuit-opening switch 50 at the lower end of the pillar 16.

10 While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short the invention includes all the modifications and embodiments coming within scope of the following claims.

15 Having thus fully described the invention, what is claimed as new, and for which it is desired to secure Letters Patent, is:

20 1. In an elevator apparatus, a supporting frame including a plurality of vertical pillars, a horizontal elevator platform mounted to move up and down within said frame, a reversible motor, a sprocket driven by said motor, a sprocket chain operated by said sprocket and connected at both ends to one side of said platform, and means to guide the front of said platform comprising two sets of concave rollers mounted in bearings rigidly secured to said platform and engaging the front and rear of the pillars located at the other side of said platform.

25 2. The invention as defined in claim 1, in which said rollers are mounted upon a downwardly spaced frame which is rigidly connected in spaced relation with said platform.

30 3. The invention as defined in claim 1, in which provision is made of a lug carried by said chain, and a pair of circuit-opening switches in alignment with the path of said lug to stop said motor when the platform has reached the end of either of its upper or lower motions respectively.

35 4. The invention as defined in claim 1, in which said sprocket chain is adjustable.

LOUIS P. BRUNETTE.
